TILT TRAY

Edmond W. Hammer, Jr., Philadelphia, Pa., assignor to the United States of America as represented by the Secretary of the Army

Application November 20, 1957, Serial No. 697,747

8 Claims. (Cl. 89—45)

The present invention relates to a tilt tray or loading device and more particularly to apparatus of the kind which will facilitate the loading of large caliber guns with relatively heavy ammunition.

In the field of ordnance employing large caliber guns, the ammunition for such guns is usually of such weight that it would be difficult for personnel to manually load the gun without some kind of apparatus to facilitate the transfer of the ammunition from one place to another. For this reason, developments in the military weapon and ammunition art have led to the use of such apparatus as ramming devices to facilitate loading the ammunition into the breech of the gun, handcarts to transport the ammunition from a source of supply to the ramming device and, in some cases, an intermediary device for transferring the ammunition from the handcart to the ramming apparatus. It is this latter type of apparatus to which the present invention is directed.

Heretofore, loading apparatus of the kind to which the present invention is directed made use of a cradle or tray onto which the ammunition is placed from the handcart. This tray is arranged for movement from an ammunition-receiving position to a loading position where the ammunition is then transferred to a ramming device. A particular disadvantage of prior art loading apparatus is found to reside in the requirement that, in moving the loading tray from the receiving position to the loading position, human effort must be expended. Another disadvantage of automatic loading devices results from portions of the rammer mechanism interfering with loading directly from the rear, thus requiring an arrangement to one side of the rammer trough which will facilitate properly locating a round in front of the rammer head.

It is, therefore, a primary object of the present invention to provide loading apparatus which will overcome the above and other disadvantages of prior art apparatus to which the present invention is directed.

It is another object of the present invention to provide a device which will be simple in construction and positive and reliable in operation.

Still further it is an object of the present invention to provide a loading device which will be semiautomatic in operation.

Another object of the invention is to provide a loading device which will enable quick and easy transfer of ammunition from one place to another with a minimum of effort on the part of the gun crew.

It is also an object of the present invention to provide a loading device particularly useful to ordnance but also applicable to the requirements of the kind wherein a mass is to be transferred from one position to another, such as may be contemplated in automation applications.

In accordance with the present invention, there is provided a loading device which employs the weight of the material to be transferred to operate the movement of the carrying tray from a load-receiving position to a loading position. The apparatus contemplates the use of a

2

pivoted cradle or tray which is disposed in a manner to locate the center of gravity of the combined weights of the mass and tray on the side of a vertical plane passing through the pivotal axis of the tray toward the loading position and above a horizontal plane extending through that pivotal axis. Releasable locking means is provided which is connected with the cradle for controlling operation of the device.

The novel features characteristic of the present invention, as well as additional objects and advantages thereof, will be better understood from the following detailed description when read in connection with the accompanying drawings in which:

Figure 1 is a side elevation of the rear portion of a gun provided with a ramming device and a preferred embodiment of the present invention;

Figure 2 is an enlarged side elevation of the preferred embodiment of the present invention shown in Figure 1;

Figure 3 is a rear elevation of the apparatus shown in Figure 2 and showing a portion of the rammer trough in broken line outline, the loading device being shown in a normal, load-receiving position with a round of ammunition disposed on the loading device;

Figure 4 is a view similar to Figure 3 but showing the apparatus in the delivery or loading position and illustrating the transfer of the projectile from the loading device to the rammer trough;

Figure 5 is a side elevation, partly in section, of the apparatus as it would appear from the opposite side of that shown in Figure 2 and showing a round of ammunition in the process of being loaded onto the loading device;

Figure 6 is a sectional view of the apparatus taken along the line 6—6 of Figure 2;

Figure 7 is a sectional view of the apparatus taken along the line 7—7 of Figure 2;

Figure 8 is a sectional view of the apparatus taken along the line 8—8 of Figure 2;

Figure 9 is a sectional view of the apparatus taken along the line 9—9 of Figure 3; and

Figure 10 is an enlarged view of a portion of the apparatus taken along the line 10—10 of Figure 2.

Referring more in particular to the drawings, wherein similar reference characters are used to designate corresponding parts throughout, the tilt tray 1 of the present invention is shown applied to a ramming device 3 associated with a large caliber gun 5. As shown in Figure 1, the tilt tray is located on the right-hand side of the rear portion of the ramming device and is bolted or otherwise attached to the side 7 of the casting that houses the rammer chain (not shown) and supports the rammer trough 9.

The tilt tray comprises a cradle or tray 11 of arcuate cross section transversely of its length which is pivotally supported by a plurality of brackets 13 attached to the rammer casting, the bracket extending in a transverse direction outwardly from the casting. The cradle or tray is so disposed that the concave surface 15 thereof faces normally upwardly and the pivotal axis thereof is disposed in spaced relation to and parallel to the loading axis of the rammer trough. At the forward end of the tilt tray, that is, the end located closest to the breech of the gun, an arm 17 is provided which extends in an upward direction. A finger 19 of arcuate cross section is pivotally attached to the upwardly extending arm. A concave surface 21 of the finger is so arranged that, together with the concave surface 15 of the tray 11, a segment of a circle of more than 180 degrees is defined.

In this manner, the concave surfaces are utilized to limit forward movement of an ammunition round by engaging the outer surface 24 of the round as it is moved for-

wardly in the process of being loaded on the tray. Inasmuch as the convex surfaces of the tray and finger define a circular segment of more than 180 degrees, it is obvious that movement of the round in a lateral direction would be prevented when the finger is held in a normal fixed position relative to the tray, as shown in Figures 3 and 8 of the drawings. A leaf spring 23 is mounted on the tray 11 in a manner to engage one end 25 of the finger and bias the finger to a normal round engaging position. A stop 27 is provided on the tray for engaging the finger within a slot 29 provided in the end 25 of the finger thereby to limit rotative movement of the finger in the one direction. Rotative movement in the opposite direction is limited by movement of the spring 23 but is sufficient to allow the round to clear the tray and finger as it rolls onto the rammer trough once the finger is released by the locking means.

In order to prevent rearward movement of the round once it is loaded on the tray or cradle 11, there is provided a retractable member 31 located at the rear portion of the cradle. The retractable member or stop comprises a detent which is mounted for slidable movement within a sleeve member 33 carried by the cradle and disposed in a position whereby the detent is capable of movement in directions, toward and away from the arcuate axis of the cradle, in the manner more particularly shown in Figure 6 of the drawings. A spring member 35 is located within the sleeve which functions to bias the detent to a normal position extending outwardly of the sleeve through an opening 37 in the cradle. The free end 39 of the detent is rounded for the purpose of cooperation with the external surface 24 of the round which will cause it to retract within the sleeve as the round is moved forwardly onto the cradle. Once the round has assumed a loaded position on the tray, the base 41 of the round will be located immediately forward of the retractable member and the latter will be forced outwardly from the sleeve by the spring 35 to serve as a stop thereby preventing rearward movement of the round.

The cradle or tray is pivotally mounted for movement between a normal ammunition-receiving or loading position, as shown in Figure 3 of the drawings and a delivery or release position, as shown in Figure 4 of the drawings. The tray is so disposed in the normal loading position that the center of gravity of the combined masses of the ammunition and the cradle or tray is located on that side of a vertical plane passing through the pivotal axis of the tray toward the delivery position of the tray and above a horizontal plane passing through that axis. Thus, it will be observed that, unless the cradle is held in a fixed position while in the loading position, the weight of the combined masses would be sufficient to rotate the cradle from the loading position to the delivery position. In order to influence return of the cradle to its normal loading position, a spring member 43 is provided and connected in any convenient manner between one of the brackets 13 and the cradle, as shown in Figure 7 of the drawings. The cradle spring 43 is so arranged that it is constantly under tension and, upon movement of the cradle to the delivery position, the tension will be increased. The parameters of the cradle spring are so selected that they will influence the cradle to return to its normal loading position after delivery of the ammunition round to the ramming trough but they are not sufficient as to overcome the additional weight of the round while it is disposed upon the cradle of the tilt tray apparatus.

In order to limit rotation of the cradle beyond intended limits of the loading and delivery positions it is essential to provide suitable stops. In order to limit rotative movement of the cradle beyond the load-receiving position, a stop 45 is provided in any convenient manner on one of the brackets 13 which will engage the cradle and arrest further movement thereof beyond the intended load-receiving position, as shown in Figure

7 of the drawings. In order to restrict the cradle against movement beyond the intended delivery position, there is provided another stop 47 disposed in any convenient manner on one of the brackets 13 which will engage the cradle and arrest movement thereof beyond the intended delivery position, as shown in Figures 4 and 7 of the drawings.

The pivotal axis of the cradle is provided by a shaft 49 journaled in the brackets 13 attached to the rammer casting, as more particularly shown in Figure 9 of the drawings. The cradle is provided with a plurality of arms 51 which extend downwardly therefrom each arm having an opening 53 adjacent to the lower ends thereof. A sleeve 55 is mounted within each of the openings and the respective sleeves are disposed in axial alignment in order to receive the pivotal shaft 49 which extends through all of the sleeve members. The sleeves are disposed in spaced apart relation along the shaft and in spaced apart relation to the brackets in such positions as to allow freedom of movement of the cradle together with the pivot shaft in axial directions and relative to the brackets. A resilient member 57 is provided between the sleeves immediately forward of each bracket and the bracket to function as a buffer member. On the opposite side of each bracket a compression spring 59 is provided on the pivot shaft between the rear portion of the bracket and the next adjacent sleeve disposed to the rear of the bracket. The compression springs function to bias the shaft 49 together with the cradle mounted thereon in a rearward direction limited only by the resilient members disposed between the bracket and the sleeve members immediately forward of the brackets. With this arrangement, it will be observed that any force which tends to drive the cradle forwardly, such as a force imparted by loading an ammunition round on the cradle when such round is restricted against forward movement by the concave surfaces of the finger 19 and the tray 11, will tend to drive the cradle and pivot shaft forwardly against the compression springs 59. Such a forwardly driving force will be opposed by the compression springs and the compression springs will tend to return the cradle and the pivot shaft to its normal position, as shown in Figure 9 of the drawings. Thus, the arrangement effects a buffer action which has the advantage of preventing damage to the ammunition round as well as the loading device.

The loading device is provided with a releasable locking arrangement for locking the cradle and finger in the normal load-receiving position. The releasable locking means comprises a pair of rods 61, 63 which are slidably carried by extensions or arms 65 attached in convenient manner to the cradle. In the preferred embodiment shown in the drawings one 61 of the rods is disposed somewhat above the cradle and extends into the bracket which supports the finger 19. The other rod 63 is disposed below the cradle and adjacent to the pivotal axis of the cradle with the forward end 67 thereof extending into an opening 69 provided in a forward bracket 71 also carried by the cradle. The rearward ends 73, 75 of each shaft are connected by a suitable handle 77. A compression spring 79, 81 is disposed on each shaft 61, 63 between a sleeve member 83, 85 attached to each shaft and an adjacent extension 65, in the manner particularly shown in Figures 2 and 9 of the drawings. The compression springs function to bias the shafts in a forward direction. The forward ends of the shafts are tapered, as at 87 in Figure 10 of the drawings, to facilitate inserting the ends into openings provided respectively in the finger and cradle members when the loading device is disposed in the normal load-receiving position. Thus, the ends of the shaft will prevent the cradle and the finger from rotating about their respective pivotal axes until the shafts are withdrawn sufficiently to release the parts.

From the foregoing, it will be observed that the load-

ing device of the present invention will be found to operate as follows. In order to load the device, an ammunition round is brought to the rear of the loading device usually in a handcart (not shown) with the round resting on the trough of the cart. The edge of the cart trough adjacent to the forward end of the round is then placed in convenient manner in abutment with the cradle 11 of the loading device. The round is then manually pushed off the cart onto the cradle. The forward movement of the round will cause the ogive of the round to engage the retractable stop 31 and force it downwardly into the sleeve 33. The round is then free to continue to move forwardly until it is stopped by the concave surfaces of the finger 19 and the tray 11 at the forward end of the cradle. Once the base 41 of the round passes over the retractable stop, the retractable stop is released and will be forced outwardly of the sleeve to prevent the round from sliding backward. During this operation the forward impact force applied to the finger and cradle is absorbed by the 2 compression springs 59 on the cradle pivotal axis. When it is desired to deliver or transfer the round to the ramming device at the rear of the gun, a member of the gun crew pulls backwardly on the handle 77 thereby withdrawing the upper and lower rods or shafts 61, 63 attached thereto from engagement with the finger and cradle respectively. The finger and cradle are, therefore, free to rotate about the respective pivotal axes and the weight of the round is sufficient to overcome the force of the cradle return spring 43 thereby to rotate the cradle and round toward the delivery position. In the delivery position, the round is free to roll off the cradle onto the rammer trough due to the freedom of movement of the finger which no longer prevents lateral movement of the round on the cradle. Once the round is delivered to the rammer trough tension of the cradle return spring 43 will influence the cradle to its normal load-receiving position and the finger spring 23 will influence the finger to its normal load-receiving position. When the cradle reaches the load-receiving position, the shafts of the releasable locking means will be urged forwardly by the springs 79, 81 to dispose the ends of the shafts into the openings provided in the cradle and the finger thereby locking the apparatus in condition for receiving the next round.

It will be apparent from the above description to persons skilled in the art that the disclosed invention provides an efficient arrangement for transferring a relatively heavy mass from one position to another. By employing the weight of the mass to effect movement of the device from one position to another, the apparatus is rendered semiautomatic. It will also be apparent to those persons skilled in the art that the arrangement is capable of adaptation to applications other than the particular ordnance application herein disclosed. Therefore, it is desired that the present invention shall not be limited except insofar as is made necessary by the prior art and by the spirit of the appended claims.

What is claimed is:

1. A loading device for transferring a mass from a receiving position to a delivery position comprising a tray pivotally mounted for oscillating movement between a receiving position and a delivery position, the pivotal axis of said tray being disposed beneath said tray and parallel to the longitudinal axis thereof, the center of gravity of said tray being disposed on that side of the

tray pivotal axis toward said delivery position, resilient means connected with said tray for normally biasing said tray to the receiving position, releasable locking means connected with said tray for controlling movement thereof, and movement of said tray toward the delivery position being responsive to the release of said tray for movement thereof solely under the influence of the weight of the mass.

2. The invention as defined in claim 1 and wherein 10 said loading device includes a finger pivotally carried by said tray and disposed in a position to limit forward and lateral movement of the mass on the tray, and wherein said locking means is connected also with said finger in a manner to effect release of said finger and said tray.

3. The invention as defined in claim 2 and wherein 15 the pivotal connection for said tray includes buffer means for absorbing shock imparted while loading said mass on said tray.

4. The invention as defined in claim 3 and wherein 20 said loading device includes means carried by said tray constituting a stop to prevent backward movement of said mass after being loaded on said tray.

5. The invention as defined in claim 4 wherein said 25 stop means is mounted for slidable movement relative to said tray, said stop means being disposed retractable from said tray in response to loading said mass on said tray.

6. A device for transferring ammunition from a receiving point to the loading axis of a gun comprising a 30 cradle pivotally mounted for swinging movement in directions transverse to the loading axis with the pivotal axis of said cradle disposed parallel to said loading axis, said cradle being so disposed that the center of gravity thereof is located on that side of a vertical plane extending through the cradle pivotal axis toward the loading axis and above a horizontal plane extending through the cradle pivotal axis, means carried by said cradle limiting movement of the ammunition while disposed on said cradle, resilient means connected with said cradle for biasing said cradle to a normal ammunition receiving position remote from the loading axis, and releasable locking means connected with said cradle for controlling pivotal movement of said cradle.

7. The invention as defined in claim 6 wherein said 45 limiting means includes a finger pivotally carried by said cradle and disposed to engage the outer surface of the ammunition in a manner to limit forward and lateral movement of the ammunition on the cradle and a retractable stop on said cradle for limiting rearward movement of the ammunition while on the cradle, and wherein 50 said releasable locking means includes means connected with said finger for release of said finger and said cradle.

8. The invention as defined in claim 7 and wherein 55 the pivotal connection of said cradle includes buffer means for absorbing shock imparted while loading said ammunition on said cradle.
